UNITED STATES PATENT OFFICE.

RICHARD T. HOSKING, OF SAGINAW, MICHIGAN.

SEAL.

1,240,719.

Specification of Letters Patent. Patented Sept. 18, 1917.

Application filed December 14, 1915. Serial No. 66,698.

To all whom it may concern:

Be it known that I, RICHARD T. HOSKING, a citizen of the United States, residing at Saginaw, in the county of Saginaw and State of Michigan, have invented certain new and useful Improvements in Seals; and I do hereby declare the following to be a full, clear, and exact description of the invention, such as will enable others skilled in the art to which it appertains to make and use the same.

This invention is a seal and pertains more particularly to the type of seal commonly employed for sealing cars, crates, shipping baskets and for similar service.

The objects of the improvement are, first, to provide a seal that can be readily stamped from a single strip of metal and that is simple in construction, and reliable in operation.

A further object is to so construct the seal that the seal cannot be opened after it has once been formed, without destroying the seal and disclosing that it has been tampered with.

With these and certain other objects in view which will appear later in the specification, my invention comprises the device described and claimed and the equivalents thereof.

In the drawings, Figure 1 is a plan view broken away in part, showing the flat strip of metal from which the seal is formed.

Fig. 2 is a view showing the two ends of the seal strip engaged.

Fig. 3 is a side view showing the seal completed.

Fig. 4 is a part sectional side view, taken on the line 4-4 of Fig. 3, the parts being greatly enlarged for purpose of better illustration.

As is clearly shown in the drawings, the device consists in a flat strip of metal 1 formed near one end with an elongated slit 2, adapted to receive the opposite end 3 of the strip, this end 3 being the seal-forming end.

To interlock the two ends of the strip to form the loop, as shown in Fig. 3, and to seal the end 3, it is only necessary to pass the end 3 through the slit 2, and to then fold the end 3 back upon itself, as shown in Figs. 3 and 4.

Ordinarily the strip 1 is made of sheet tin, or equivalent material, which will enable the end 3 to firmly retain its folded po-

sition against any effort to forcibly draw it through the slit 2, the slit 2 being of sufficient width and length to receive the end 3, but being too narrow to permit the withdrawal of the end 3 after it has been folded back upon itself, in the manner shown.

The seal end may be easily folded between the thumb and finger, or it may be folded by means of any suitable tool.

The material of which the strip is made, such as sheet tin, is capable of being folded without cracking or breaking, but if it is afterward unfolded it will break along the crease, thus destroying the seal.

To further obviate any possibility of tampering with the seal by unfolding the end 3, I preferably form the curved slit 4 in the strip 1 at the line where the fold is to take place, thus leaving a projecting tongue 5 on the strip 1 after the end 3 has been folded, as shown in Figs. 3 and 4, thereby rendering it necessary, in order to withdraw the end 3 through the slit 2, to unfold the end 3 until it is perfectly flat, so it lies in the plane of the strip 1 and by making it necessary to flatten the seal before it can be withdrawn, the breaking of the seal is made still more certain.

In order to avoid any possibility of filing or otherwise sharpening the extremity of the seal end 3 and forcibly drawing it out through the slit 2, I preferably further insure the locking of the seal by folding it on a diagonal line, as at X-X in Fig. 2. When so folded, one corner of the end 3 will project slightly beyond the lateral edge of the strip 1 and beyond the end of the slit 2, as shown in Fig. 3, so that it becomes impossible to withdraw the seal through the slit 2 without entirely flattening the seal end and thereby cracking the material and destroying the seal.

To prevent the end 3 from becoming pushed too far through the slit 2 when the slit is assembled, I prefer to provide a suitable projection in the strip 1. The projection serves as a stop to limit the distance that the end 3 can be pushed through the opening 2 and the projection may be conveniently formed of letters or numbers such as are usually stamped on strip seals of this character. Such a projection or letter is shown at 6.

As a still further safeguard against tampering and to insure the breaking of the metal if the seal is straightened, I may also

provide notches 7, 7 in the two edges of the strip 1 and located at the ends of the line of folding, as at X—X. These notches insure the breaking of the metal when the seal end 3 is unfolded, but do not impair the holding strength of the seal itself so long as it is not tampered with.

By the means above described, I have produced a simple, inexpensive, yet strong and reliable seal that may be readily attached to a car or other structure, that does not depend upon the automatic catching of a spring or like member, but has its seal formed by manually bending the end of the strip after the end has been passed through the slit 2, and since the sealing member is always visible, the effect of any tampering is at once discernable.

Having thus described my invention, what I claim and desire to secure by Letters

Patent is:—

1. A seal comprising an elongated metal strip having a narrow slit formed near one end, the opposite end of said metal strip inserted in said slit and projecting through said strip, a curved slit formed in said strip, a tongue included within said curved slit, the projecting end of said strip doubled upon itself to form a stop of greater thickness than the width of the slit to prevent withdrawal of the doubled end through the slit.

2. A seal comprising a single strip of metal having a narrow elongated slit formed near one end, the strip being bent to form a loop and the opposite end of said metal strip inserted in the slit and projecting through said strip, a curved slit formed in said strip, a tongue included within said curved slit, the projecting end of said strip doubled upon itself along a diagonal line across said strip to form a laterally projecting stop of greater thickness than the width of the slit, to prevent withdrawal of said double end through said slit.

3. A seal comprising a single strip of metal having a narrow elongated slit formed near one end, the strip bent to form a loop and the opposite end of said strip in-

serted in said slit and projecting through the strip, a slit formed in said strip, to include a tongue, the projecting end of said strip folded back upon itself at the sides of the tongue to form a stop of greater thickness than the width of the slit, to prevent withdrawal of the folded end and tongue through said slit.

4. A seal comprising a single elongated strip of metal having a narrow elongated slit formed near one end, the strip being bent to form a loop and the opposite end of said metal strip inserted in said slit and projecting through said strip, a slit formed in said strip, a tongue included within said slit, the projecting end of said strip folded back upon itself to form a stop of greater thickness than the width of the slit, to prevent withdrawal of the folded end and tongue through said elongated slit.

5. A seal comprising a metal strip having a narrow elongated slit formed near one end, the opposite end of said strip inserted in said slit and projecting through said strip, a curved slit formed in said strip, a tongue, diagonally disposed notches formed in the opposite edges of said strip, the projecting end of said strip folded back upon itself along the line of said notches to form a stop to prevent withdrawal of the folded end and tongue through said elongated slit.

6. A seal comprising a metal strip having a narrow slit formed near one end, the opposite end of said strip inserted in said slit and projecting through said strip, a curved slit formed in said strip, a tongue, diagonally disposed notches formed in the opposite edges of said strip, the projecting end of said strip folded back upon itself along the line of said notches, and raised projections formed in the body of said strip, for the purposes set forth.

In testimony whereof I affix my signature in presence of two witnesses.

RICHARD T. HOSKING.
